RAIL AND WHEEL FLANGE LUBRICATOR

Curtis A. McRee, Hamlet, N. C.

Application August 27, 1931, Serial No. 559,802

5 Claims. (Cl. 184—3)

My invention relates to automatic lubricating devices for the rails of a railway track and the flanges of the wheels of the rolling stock passing thereover.

It is an object of the invention to provide a device of this character which may be readily installed in operative position at any desired point along the track without the use of special tools and without altering the track structure in any way.

Another object of the invention is to provide a lubricator which will project the lubricant to the point of frictional contact of the wheel flanges with the rail head and which will simultaneously apply the lubricant to both the flange and rail.

A further object of the invention is to provide means operable by the passage of the thread of the wheels thereover for automatically and positively forcing the lubricant to the desired point.

A still further object of the invention is to provide a device of this character with a lubricant chamber and in connection therewith to provide a lubricant reservoir with means for maintaining the chamber supplied with lubricant and to connect a plurality of spaced lubricator units to one reservoir to be simultaneously supplied with lubricant therefrom.

Other objects and advantages of the invention will become apparent during the course of the following detailed description when read in conjunction with the accompanying drawings which form a part of this specification and in which,

Figure 1 is a cross section of a railway track with my improved lubricator applied to one of the rails thereof;

Fig. 2 is an enlarged view of the lubricant applicator shown in Fig. 1;

Fig. 3 is a side elevation thereof;

Fig. 4 is a top plan view thereof;

Fig. 5 is a vertical sectional view taken on the line 5—5 of Fig. 4;

Fig. 6 is a horizontal sectional view taken on the line 6—6 of Fig. 5;

Fig. 7 is a side elevation of the applicator taken from the gauge side of the rail;

Fig. 8 is a side elevation partly in section of the oil reservoir;

Fig. 9 is a side elevation thereof with the parts in operative position for refilling the same;

Fig. 10 is a top plan view thereof with the cover removed;

Fig. 11 is a diagrammatic view showing my system installed on a section of track.

Referring now more particularly to the draw-

ings wherein like numerals refer to like parts throughout the same, and wherein a preferred embodiment of the invention has been shown by way of example, 15 indicates one of the rails of a conventional railroad track 16 and 17 indicates a portion of one of the wheels of the rolling stock passing over said track.

The lubricant applicator unit 18 is mounted at one side of the rail 15 opposite the gauge side thereof and in practice there may be any number of the applicator units 18, spaced from each other around a curve in the track as may be deemed necessary to effect proper lubrication of the wheels and track. An oil reservoir 19, situated at one side of the track is connected to each of the applicator units 18 whereby to keep them supplied with a sufficient quantity of lubricant at all times.

The applicator units 18 are supported by means of a bracket 20 which is clamped to the rail 15. The bracket 20 comprises a pair of opposed clamping members 21 and 22 which have their opposed faces formed to fit the flange and web portions 23 and 24, respectively, of the rail 15. The clamping member 22 is formed with a pair of spaced horizontal lugs 25 which engage under the flange 23 of the rail 15 and the clamping section 21 is also formed with a horizontal portion 26 which engages under the flange 23. The flange engaging portion 26 of the clamping member 21 is formed with a forwardly extending projecting portion 27 centrally thereof which extends between the lugs 25 on the clamping member 22 thereby insuring that the clamping members will be correctly aligned when assembled on the rail. A pair of tie bolts 28 extending through the lugs 25 and the flange engaging portion 26 serve to tie the clamping members 21 and 22 together and to bind them fast upon the rail 15.

The clamping member 22 is formed with a horizontal step or seat portion 29 for the reception of a lubricant chest or chamber 30, the bottom of which is formed with a lateral flange 31 which is secured by means of bolts 32 to the lateral flange 33 formed with the step portion 29 of the clamping member 22. The upper edges of the side walls 30 of the chest 18 are formed with a flange 34 to which the cover plate or top 35 of the chest 30 is fastened by means of the bolts 36.

A pump cylinder 37 is mounted within the lubricant chamber 30 between the cover plate 35 and the bottom wall 38 thereof, the end of said cylinder being received within openings 39 and 40 in the cover plate and bottom wall respectively. The cylinder 37 is provided with an annular shoulder 41 adjacent each end thereof, the

shoulders 41 bearing against the inner faces of the cover plate 35 and bottom wall 38, respectively. A double acting piston 42 is mounted for reciprocation within the bore 43 of the cylinder 37, the piston 42 being mounted upon the lower end of the piston rod 44 which extends vertically through a cylinder head 45 which is threaded into the upper end of the bore 43 of the cylinder 37. The cylinder head 45 is provided with an annular flange 46 which engages the upper face of the closure plate 35 around the opening 39 and serves to clamp said plate between the cylinder head and the flange 41.

An outlet fitting 47 is threadedly engaged with in the lower end of the bore 43 of the cylinder 37 and is provided with an annular flange 48 for cooperation with the flange 41 on the lower end of the cylinder in clamping the bottom 38 therebetween. The fitting 47 is provided with a lubricant passage 49 in communication with the interior of the cylinder 37, said passage being normally closed by means of a ball valve 50 which is normally urged to its seat 51 by means of a spring 52. A suitable semi-flexible conduit or pipe 53 connected at one end to the outlet fitting 47 serves to convey the lubricant discharged from the pump to the nozzle 54 from which the lubricant is discharged on to the wheel flange 55 and the side 56 of the rail 15.

The pump piston 42 is normally urged to its uppermost position by means of a coil spring 57 interposed between said piston and the fitting 47. Suitable inlet ports 58 are formed in the side walls of the cylinder 47 for the passage of lubricant from the chamber 30 into the bore 43 of the cylinder 37 upon the up-stroke of the piston 42, suitable ball check valves 59 being provided in said inlet ports to prevent the return of the lubricant back into the chamber 30 upon the down stroke of the piston.

Operation of the piston 42 and piston rod 44 is effected through the medium of a plunger 60 which is mounted for vertical reciprocation within the bore 61 of a suitable housing 62 which is mounted upon the cover plate 35 over the cylinder head 45 and is secured in place by means of bolts 63. The upper end of the plunger 60 is provided with a contact shoe 64 normally protruding above the level of the rail 15 and adapted for engagement by the tread portion of the wheel 17 to effect downward movement of the plunger 60, piston rod 44 and piston 42, to force a charge of oil from the cylinder 37 through the conduit 53 and nozzle 54 to lubricate the flange of said wheel and the side of the rail head.

The lower end of the plunger 60 is formed with a socket 65 for the reception of a head 66 carried by the upper end of the piston rod 44 and an expansible coil spring 67 surrounding said rod 44 between the head 66 thereof and the cylinder head 45 serves to normally urge and maintain the plunger 60, piston rod 44 and piston 42 in their uppermost positions, this action also being aided by the coexpansible coil spring 57 below the piston 42.

Adjustment of the stroke of the piston 42 and thus the volume of lubricant discharged by the passage of each wheel of the rolling stock over the contact shoe 64 is provided through the medium of an adjustable stop 68 disposed in a vertical slot 69 formed in the side of the plunger 60, upward movement of the plunger 60 being limited by contact of the bottom of the slot 69 with the stop 68. This stop 68 takes the form of a detent or pin protruding from one side of the end of the

rotatable plug 70 which is mounted for rotation about a horizontal axis in the wall of the housing 62. The opposite end of the plug 70 is reduced in diameter as at 71 and is received within a socket 72 in a boss 73 of a rotatable adjusting plate 74, said reduced end being secured within said boss for rotation with said plate through the medium of a pin 75. The adjusting pin 75 is rotatably mounted by having the boss 73 thereof fitted within the enlarged outer end of the bore 76 within which the horizontal plug 70 is rotated. It will be readily seen that rotation of the plate 74 will result in raising or lowering of the eccentrically mounted stop 68 thereby effecting an adjustment of the stroke of the piston 42 in the manner above described. The adjusting plate 74 may be locked in any position of adjustment by reason of a pair of locking screws 77 which extend through spaced holes 78 in said adjusting plate and screw into aligned openings in the housing to lock the plate to said housing.

In order to prevent undue lateral strain and wear upon the plunger 60 when the tread of the wheel 17 strikes the contact shoe 64, said shoe is provided with spaced depending lugs 79 which extend downwardly at opposite sides of the housing 62, the opposed faces of said lugs being provided with tongues 80 which fit in vertically aligned grooves 81 formed with the housing 62 thereby forming a guide for the shoe 64 and preventing the strain upon the plunger 60.

It will be seen from an inspection of Figs. 3, 5 and 7 that the step portion 29 of the clamping member 22 is cut away as at 82 to accommodate the fitting 47 and the lubricant delivery pipe 53, which pipe, as before stated, has its receiving end secured to the fitting 47 in communication with the lubricant passage 49 thereof. The lubricant pipe 53 leads from the fitting 47 downwardly between the lugs 25 and the clamping plate 22 and 110 then under the rail 15 and through a channel 83 formed with the clamping member 21, the flange engaging portion 26 and the projection 27 thereof, the channel 83 extending transversely of the rail 15. When the pipe 53 reaches the side of the rail 15 opposite its receiving end, it is bent back upon itself as at 84 to overlie that portion of the flange 23 which is engaged by the clamping member 21, the terminal portion 85 of said pipe 53 being bent upwardly between the furcations 86 115 of the bifurcated portion of the clamping member 21 which engages the web portion 24 of the rail 15. The nozzle 54 is threadedly secured on the upturned end 85 of the pipe 53 and said nozzle and pipe are rigidly held in the proper position by means of brace plates 87 and 88 respectively which extend between the furcations 86 and are secured thereto by means of screws 89.

In operation, the lubricant chamber 30 being mounted upon the outside of the rail 15, the shoe 54 will be contacted by the tread portion of the wheel 17 of the rolling stock passing thereover and the piston 32 will be depressed through the medium of the plunger 60 and piston rod 44 to force a charge of lubricant past the ball valve 50 and through the lubricant pipe 53 and thence out of the nozzle 54 to be discharged at the point of frictional contact between the flange 55 and the side of the rail head 56 on the gauge side of the rail. The ball valve 50 serves the dual purpose of preventing the piston 32 from drawing the lubricant back through the pipe 53 upon the upstroke thereof and also prevents any unintended flow of lubricant from the reservoir 30 through said pipe 53 when there are no cars passing over 145

the track 16. When it is desired to regulate the amount of lubricant to be forced from the nozzle 54 upon the passage of each wheel over the applicator the locking screws 77 are removed from the 5 adjusting plate 74 and said plate is turned in a direction to either raise or lower the eccentrically mounted detent 68 so as to restrict the upward movement of the plunger 60 and thus the piston 42.

10 As the size of the lubricant chambers 30 are necessarily restricted due to the placement of the applicator units directly upon the rail 15, I have provided a lubricant reservoir for automatically maintaining the chambers 30 full of lubricant 15 without requiring constant attention of a track attendant. A single large lubricant reservoir 19 is preferably sunk in the ground to one side of the track 16 intermediate of a row of applicator units, said reservoir communicating with a main 20 distributor pipe 89 from which branch pipes 90 lead to the respective lubricant chambers 30 of the individual applicator units.

The lubricant reservoir 19 shown in detail in Figs. 8, 9 and 10 comprises a cylindrical drum 91 which is to be filled with suitable oil or other lubricant 92. A weighted piston 93 having a snug sliding fit within the cylinder 91 serves to maintain a pressure upon the oil within said cylinder to force the same out of the delivery pipe 94 which 30 leads from the bottom of the cylinder to the distributor pipe 89. It will thus be seen that a constant supply of lubricant under pressure is always maintained within the lubricant chamber 30 of the respective units and it may here be noted that the spring 52 of the ball valve 50 is of such strength as to prevent said pressure from forcing the oil or other lubricant past said valve and through the pipe 53 when no trains are passing over the track 15. When the lubricant within 40 the reservoir 19 has become exhausted, the piston 93 is drawn to its uppermost position through the medium of a crank operated winch 95 which is connected by means of a chain 95^a to the upper face of the piston 93. The winch 95 is carried on 45 a collapsible tripod made up of extensible legs 96 which are pivotally secured at their lower ends to the upper edges of the cylinder 91 at spaced intervals in any suitable manner. When the tripod is in collapsed position, the winch is lowered so 50 that the hinged cover plate 97 may be closed and locked to prevent unauthorized persons from tampering with the lubricant reservoir.

The weighted piston 93 includes the removable plug 98 which is secured in an opening in said piston by means of wing screws 99 so that said plug may be readily removed to allow lubricant to be introduced through the opening normally occupied thereby when the piston has been drawn to the top of the cylinder by the winch mechanism 55 95. It will be noted that the plug 98 is formed of extra heavy material so as to provide the necessary weight for maintaining the pressure upon the lubricant within the reservoir cylinder 91. It will thus be seen that all of the applicator units 18

will have their lubricant chambers constantly supplied with lubricant from the large reservoir 19 and that my improved lubricator will operate efficiently over a long period of time without any attention whatsoever.

80 Although a preferred embodiment of the invention has been shown and described, it will be understood that various changes in the details of construction may be made without departing from the spirit of the invention as defined by the appended claims.

85 I claim:

1. In a rail lubricator, a pair of clamping members, a lubricant chest carried by one of said clamping members, lubricant expelling means operable in said chest, a discharge nozzle carried by the other clamping member, a conduit leading from said nozzle to the expelling means, and interengageable means to align the clamping members.

90 2. In a rail lubricator, a pair of clamping members, a lubricant chest carried by one of said clamping members, lubricant expelling means operable in said chest, a discharge nozzle carried by the other clamping member, a conduit leading 100 from said nozzle to the expelling means, and means interengageable beneath the rail flange to align the clamping members.

95 3. In a rail lubricator, a pair of clamping members, a lubricant chest carried by one of said clamping members, lubricant expelling means operable in said chest, a discharge nozzle carried by the other clamping member, a conduit leading 105 from said nozzle to the expelling means, and means interengageable beneath the rail flange to align the clamping members, said means comprising a pair of spaced lugs on one of the clamping members and an extending portion on the other clamping member to enter the space between the lugs.

110 4. In a rail lubricator, a pair of clamping members, a lubricant chest carried by one of said clamping members, lubricant expelling means operable in said chest, a discharge nozzle carried by the other clamping member, a conduit leading 115 from said nozzle to the expelling means, means interengageable beneath the rail flange to align the clamping members, and tie means to tie the clamping members together and bind them fast to the rail.

120 5. In a rail lubricator, lubricant expelling means situated on one side of the rail, a lubricant nozzle on the other side of the rail, a conduit connecting the nozzle with the expelling means, and means for at once supporting the expelling means and 130 nozzle and guarding the conduit, said means comprising a pair of clamping members situated on opposite sides of the rail and having interengageable means connected beneath the rail, one of said members being cut-away and the other member 135 channeled to provide a chamber for the occupancy of the conduit.

CURTIS A. McREE.
